NEEDLE MOTION

Albert R. Clairmont, Amsterdam, N. Y., assignor
to Mohawk Carpet Mills, Inc., Amsterdam, N. Y.,
a corporation of New York

Application September 14, 1945, Serial No. 616,164

11 Claims. (Cl. 139—123)

1

This invention relates to looms in which needles are employed for inserting shots of weft or filling yarns into warp sheds in the production of fabrics. More particularly, the invention is concerned with a novel needle motion for use in such looms, which makes possible the insertion by the needle of yarns of different kinds drawn from separate supplies. The new selective needle motion includes means controlled by a pattern for presenting the different yarns to the needle for insertion thereby in a predetermined sequence, and, by the use of yarns of different color, for example, and an appropriate pattern element, the needle motion may be employed in the production of fabrics varying in pattern effects.

The needle motion of the invention comprises a needle having an open eye and means for advancing and retracting the needle to effect insertion of weft shots thereby. The weft yarns drawn from their supplies are controlled by guides, which may be moved to and from positions in which their yarns are engaged by the needle and carried along thereby during the inserting movement of the latter. Each yarn is further controlled by holding means normally preventing the yarns from being drawn from the supplies and a releasing means is provided for each holding means. A pattern device, including a pattern element, controls the movement of the guides to cause them to present their yarns to the needle in an order determined by the pattern element, and, whenever the device selects and causes a guide to move to present its yarn to the needle, the device cooperates with other means to cause the releasing means for the holding means acting on that yarn to free the yarn during the inserting movement of the needle. The yarns are, accordingly, inserted into the fabric in a predetermined order and are held against movement at all times, except when they are being inserted.

For a better understanding of the invention, reference may be made to the accompanying drawings, in which

Fig. 1 is a view in plan of a loom equipped with the new needle motion, parts of the loom being omitted;

Fig. 2 is a view of the loom in front elevation;

Fig. 3 is a view of the loom in side elevation looking from the left in Fig. 2;

Fig. 4 is a wiring diagram; and

Fig. 5 is a view in side elevation of the yarn holding and releasing means.

The loom shown in the drawings includes the usual sides 10, between which heddle frames 11

2

are suspended and actuated by the usual mechanism (not shown) from cams 12 on a shaft 13 to form sheds of warp yarn 15 drawn from a beam (not shown). The shots of weft or filling are inserted by a needle 16 and are then beaten up by a lay 17. The completed fabric 18 is taken up by means of a spike roll 19, which is driven by a gear 20 on its shaft meshing with a gear 21 fast on shaft 22. A ratchet wheel 23 fast on shaft 22 is engaged by a pawl 24 attached to an arm 25 fast on a shaft 26 supported on the loom sides. An arm 27 fast on the shaft is connected by a rod 28 to an arm 29 secured to the lay, so that on each beat-up of the lay, the ratchet wheel 23 and its shaft 22 are advanced by one step.

The needle 16 is attached to a carriage 30 slidable along a guideway 31 at the top of an extension 32 from one of the loom sides, and the needle carriage is actuated from shaft 33 connected by bevel gearing 34 to the heddle cam shaft 13. Shaft 33 carries an arm 35 connected by a link 36 of adjustable length to a lever 37 pivotally mounted on an extension 38 from the loom side. A rod 39 connects the lever to one end of a link 40, the other end of which is connected to the needle carriage. As shaft 33 rotates, the needle is moved back and forth through the successive frames.

The needle is of the open eye type, and weft yarns 41a, 41b, 41c from a plurality of supplies 42 mounted on suitable supports in any convenient location are presented in a predetermined sequence to the needle for insertion in the fabric. The selective needle motion of the loom shown is constructed to handle three different weft yarns drawn from individual supplies thereof, and it includes three yarn guides 43a, 43b, 43c, which are mounted on the ends of respective rods 44 extending through respective solenoids 45a, 45b, and 45c supported in any convenient manner on the loom side adjacent the extension 32. Each rod 44 is attached to a core or plunger (not shown) within its solenoid and is encircled by a spring 46 which bears at one end against the solenoid and at the other against a head 47 at the end of the rod opposite to that which supports the yarn guide. The springs tend to hold the rods with their yarn guides away from the path of the needle, but upon energization of any of the solenoids 45, its plunger is moved to project its rod toward the path of travel toward the needle, so that the yarn guide carried by the rod holds its yarn in position to be picked up by the

needle and carried thereby into a shed of warp threads.

The yarns drawn from the supplies pass through respective traps, each of which comprises a stationary block 48 mounted on a suitable support 49, and a movable block 50 attached to one end of a lever 51 pivoted in standards 52 rising from support 49. A spring 53 acts on each lever and tends to swing it to force block 50 against block 48. The other end of each lever is connected by a rod 54 to a core within one of solenoids 55a, 55b, and 55c and, when the solenoid is energized, lever 51 is swung to open the trap by raising block 50 from block 48. The yarns from the respective supplies pass upward and over the top of support 49 through guides 56, across blocks 48, and through guides 57. Beyond each guide 57, each yarn passes through an eye 58 at one end of a lever 59 pivoted on standards 52. The other end of the lever is connected by a spring 60 to the end of a lever 51 adjacent the block 50 thereon. From the eyes 58, the yarns pass through stationary guides 61 and then to the guides 43a, 43b, 43c.

A pattern drum 62 is mounted on shaft 22 and it carries pattern projections 63a, 63b, 63c, on its surface. Three micro-switches 64a, 64b, 64c are mounted adjacent the periphery of drum 62, and each switch is actuated by a stem 65 having a roller 66 at its end. The rollers lie in position to be engaged by respective pattern projections 63a, 63b, 63c and the projections are properly spaced angularly about the surface of the drum, so that, at any instant, only one projection engages the roller on the stem of its associated micro-switch. When a pattern projection engages the roller, it forces the stem inwardly relative to the switch and causes the switch to be closed. The switches control the supply of current to the respective solenoids 45a, 45b, and 45c, which control the weft yarn guides 43a, 43b, 43c.

A cam drum 67 is mounted on shaft 33 and the drum is provided with an high arcuate portion which engages rollers 68 on stems 69 of respective micro-switches 70a, 70b, 70c. As the drum 67 rotates, it acts on the rollers and stems to close all of the micro-switches at the same time. These switches control the supply of current to respective solenoids 55a, 55b, and 55c which release the traps which otherwise prevent movement of the arm from the supplies.

As shown in the wiring diagram of Fig. 4, the micro-switches 64a, 64b, 64c are in parallel connections from a source of power indicated at 71 to respective solenoids 45a, 45b, 45c, which control yarn guides 43a, 43b, 43c. The micro-switches 70a, 70b, 70c are in lines by which respective solenoids 55a, 55b, 55c are connected in parallel with solenoids 45a, 45b, 45c.

In the operation of the loom, the pattern drum 62 is advanced one step for each beat-up of the lay, that is, for each advance and return movement of the needle. At each period of rest of the drum 62, one or the other of the micro-switches 64a, 64b, and 64c is closed by the action of a pattern projection 63a, 63b, or 63c, on the stem 65 of one of the micro-switches. The closure of a switch, for example, 64a, causes current to be supplied to its yarn guide solenoid 45a, and the yarn guide 43a acted on by that solenoid is then moved to a position in which the weft yarn 41a carried thereby lies in the path of the eye of the needle. Shortly after the needle starts its forward movement into the shed, the high portion of the drum 67 acts on the plungers of all the micro-

switches 70a, 70b, and 70c to close those switches. However the closure of the micro-switches 70a, 70b, and 70c will cause only one of the solenoids 55a, 55b, and 55c to be energized, because only one of the switches 64a, 64b, and 64c had been closed at the time. With the energization of one of the solenoids 55a, 55b, or 55c, the trap controlling the yarn being presented to the needle by its guide 43a will be opened and the yarn will thereupon be released so that it can be carried into the shed by the needle.

When the inserting movement of the needle has stopped, cam 67 will have moved angularly to present a low spot to the stems 60 of micro-switches 70a, 70b, and 70c and all of those switches will open. The trap, which has been opened to free the yarn, will then be closed by the action of its spring 53, and the yarn will be held against further movement during the return movement of the needle. During the time when the needle has begun its inserting movement but the trap of the yarn, which is being inserted, is still closed, the pull of the needle on the yarn will depress the lever 59, through the eye 58 of which the yarn is being drawn. When the needle reaches the end of its advancing movement and the yarn that has been inserted thereby is again clamped by its trap, the lever 59 will be swung upwardly by its spring 60 to take up any slack in the yarn beyond the trap.

In the loom illustrated, the selective needle motion is constructed to handle yarns from three different supplies, but it will be apparent that by the addition of another row of pattern projections 35 on drum 62 and the use of additional movable yarn guides, traps, and their associated parts, the needle motion may be constructed to handle an increased number of yarns. Also, instead of using a pattern drum 62, various other common pattern devices may be employed for controlling the micro-switches 64a, 64b, and 64c.

The claims are:

1. In a loom having a needle for inserting weft shots into sheds of warp yarns to produce a fabric, the combination of means for holding a plurality of supplies of weft yarn, movable yarn guides for the yarns from the respective supplies, solenoid means for moving the guides to cause them to present their yarns to the needle for insertion thereby, solenoid means for releasing the holding means, and pattern means for selectively energizing the solenoid means for moving the guides and thereafter energizing the solenoid means releasing the means holding the yarn presented to the needle by its guide.

2. In a loom having a needle for inserting weft

shots into sheds of warp yarns to produce a fabric, the combination of means for holding a plurality of supplies of weft yarn, movable yarn guides for the yarns from the respective supplies, separate electrical means for moving the respective guides to cause them to present their yarns to the needle for insertion thereby, separate

means normally holding respective yarns against movement from the supplies, electrical means for releasing the individual holding means, and pattern means for selectively operating the guide moving means and thereafter operating the releasing means for the holding means for the yarn

controlled by the guide moved by the selected moving means.

3. In a loom having a needle for inserting weft

shots into sheds of warp yarns to produce a fabric, the combination of means for holding a plu-

rality of supplies of weft yarn, movable yarn guides for the yarns from the respective supplies, electrical means for moving the guides to cause them to present their yarns to the needle for insertion thereby, means normally holding the yarns against movement from the supplies, electrical means for releasing the holding means, and means, including pattern means, for selectively operating the moving means and for thereafter operating the releasing means during the inserting movement only of the needle.

4. In a loom having a needle for inserting weft shots into sheds of warp yarns to produce a fabric, the combination of means for holding a plurality of supplies of weft yarn, movable yarn guides for the yarns from the respective supplies, electrical means for moving the guides to cause them to present their yarns to the needle for insertion thereby, means normally holding the yarns against movement from the supplies, electrical means for releasing the holding means, switches controlling the respective releasing means, pattern controlled means for selectively operating the moving means to cause a yarn to be presented to the needle, and means for actuating the switch of the releasing means for the holding means for said yarn to cause the yarn to be released as the needle moves into the shed and to be held when the inserting movement of the needle ends.

5. In a loom having a needle for inserting weft shots into sheds of warp yarns to produce a fabric, the combination of means for holding a plurality of supplies of weft yarn, movable yarn guides for the yarns from the respective supplies, a plurality of electrical means for moving the respective guides to cause them to present their yarns to the needle for insertion thereby, a switch for controlling each moving means, a plurality of means for holding respective yarns against movement from the supplies, an electrical means for releasing each of the holding means, the releasing means being connected in parallel with the corresponding moving means, switches controlling the individual releasing means, pattern controlled means for selectively closing the switches controlling the moving means, and means operable to close all the switches controlling the releasing means when the needle starts its inserting movement, and to open all said switches when the inserting movement of the needle has ended.

6. In a loom having a needle for inserting weft shots into sheds of warp yarns to produce a fabric, the combination of means for holding a plurality of supplies of weft yarn, movable yarn guides for the yarns from the respective supplies, a plurality of electrical means for moving respective guides to cause them to present their yarns to the needle for insertion thereby, a source of power connected to the moving means, switches in the connections for controlling the supply of power to individual holding means, a plurality of means for holding respective yarns against movement from their supplies, electrical means for releasing individual holding means, said releasing means being connected in parallel to corresponding moving means, switches controlling the supply of current to the releasing means, pattern controlled means for operating the moving means switches selectively, and means for closing all the releasing means switches, when the needle starts its inserting motion, and closing said switches when the inserting motion of the needle has ended.

7. In a loom having a needle for inserting weft

shots into sheds of warp yarns to produce a fabric, the combination of means for holding a plurality of supplies of weft yarn, movable yarn guides for the yarns from the respective supplies, means urging the respective guides to positions remote from the needle, means for moving the guides to cause them to present their yarns to the needle for insertion thereby, spring actuated means normally holding the yarns against movement from the supplies, means for releasing the holding means, and pattern means for selectively actuating the guide moving means and thereafter operating the releasing means corresponding thereto during the insertion of the needle only.

15 8. In a loom having a needle for inserting weft shots into sheds of warp yarns to produce a fabric, the combination of means for holding a plurality of supplies of weft yarn, movable yarn guides for the yarns from the respective supplies, means urging the respective guides to a position remote from the needle, electrical means for moving the individual guides to cause them to present their yarns to the needle for insertion thereby, spring actuated means normally holding the individual yarns against movement from the supplies, electrical means for releasing the holding means, and pattern means for selectively actuating the guide moving means and thereafter operating the releasing means corresponding thereto, said releasing means being rendered ineffective by the pattern means when the inserting movement of the needle ends.

9. In a loom having a needle for inserting weft shots into sheds of warp yarns to produce a fabric, the combination of means for holding a plurality of supplies of weft yarn, movable yarn guides for the yarns from the respective supplies, springs urging the respective guides away from the needle, solenoids associated with the respective guides and operable to move the guides to present their yarns to the needle for insertion thereby, spring actuated means for holding the individual yarns against movement from the supplies, solenoids associated with the respective holding means and operable to render such holding means ineffective, a source of power, pattern means for connecting the source selectively to the yarn guide solenoids to cause the latter to operate one at a time, and means for connecting the solenoid of the holding means corresponding to the selected yarn guide solenoid to the source of power during the inserting movement of the needle.

10. In a loom having a needle for inserting weft shots into sheds of warp yarns to produce a fabric, take-up means for the fabric, a lay, and means operated by the lay for driving the take-up means, the combination of means for holding a plurality of supplies of weft yarn, movable guides for the yarns from the respective supplies, means for moving the guides to cause them to present their yarns to the needle for insertion thereby, traps for the respective yarns, and pattern means for selectively operating the guide moving means and thereafter releasing the trap acting on the yarn, the guide for which has been moved, said pattern means including a pattern element connected to a part of the means driving the take-up means and advanced step-wise thereby.

11. In a loom having a needle for inserting weft shots into sheds of warp yarns to produce a fabric and a lay for beating up the inserted shots, the combination of means for holding a plurality of supplies of weft yarns, traps for the individual

yarns, movable guides for the individual yarns, means for moving the guides to cause them to present their yarns to the needle for insertion thereby, and pattern means for selectively operating the guide moving means and thereafter releasing the yarn, the guide for which has been moved, said pattern means including a pattern element advanced step-wise by the lay.
